UNITED STATES PATENT OFFICE.

ARTHUR C. DAMAN, OF DENVER, COLORADO.

OIL FEEDER FOR FLOTATION MACHINES.

Application filed January 12, 1924, Serial No. 685,932. Renewed August 15, 1925.

This invention relates to oil feeders, more particularly of the type adapted for use in feeding oils and other re-agents to flotation machines, and similar apparatus requiring a steady and minutely-adjustable flow of oil, and has for its principal object the provision of a device of this character, in which the amount of oil delivered may be minutely adjusted, and in which there will be no wear or friction between the oil delivering, or measuring parts.

In the usual type of oil feeder, in which a scraper removes the oil from a disk or drum, it has been found that when the scraper is set for any length of time to scrape from only a portion of the disk or drum it becomes so worn at the contacting part that it is useless when it is desired to adjust the scraper to contact with a larger portion of the disk or drum.

In this invention there is no contact whatever between the delivering trough and the oil containing parts, so that the objection to the former machines has been eliminated.

Another object of the invention is to provide a device of this character, in which the oil in the sump is constantly mixed and agitated, so that its consistency will always be uniform.

Other objects and advantages reside in the detail construction of the invention, which result in simplicity, economy, and efficiency, and which will become more apparent from the following description.

In the following detailed description of the invention reference is had to the accompanying drawing which forms a part hereof. Like numerals refer to like parts in all views of the drawing and throughout the description.

In the drawing:

Fig. 1 is a side elevation of the complete invention in which the longest part of the drum is shown upward.

Fig. 2 is a partial plan view of the invention, in which the longest part of the drum is shown downward.

Fig. 3 is a detail view of an oil lifting cup.

Fig. 4 is a detail section through the free edge of the drum.

Fig. 5 is a detail view of the clamp 19.

Let the numeral 10 designate a bearing, supported on a pedestal 11, which may be secured to any desired base 12. Bearing 10 supports a shaft 29, which carries at its one

extremity a belt pulley 30, and at its other extremity a hollow cylindrical drum 13.

The free edge of the drum 13 is cut at an angle to the axis of the shaft 29, as shown on the drawing, and is provided with a series of oil cups 14, secured thereto by means of clips 15. The interior surface of the drum 13 is provided with angularly disposed lifter bars 16. The free edge of the drum 13 is rolled backward on the inside as shown in Fig. 4 to form a peripheral groove 22. An outward projecting bead 23 is formed around the drum adjacent the clips 15.

The lower part of the drum 13 extends into an oil pan or sump 17, carried upon the base 12, and having secured to its one end a bracket 18, which is provided with a clamp 19, shown in detail in Fig. 5.

A trough 20 is arranged to be clamped within the clamp 19, by means of a set screw 21, and projects at an upward angle from the clamp 19, into the interior of the drum 13.

The operation of the device is as follows:

Oil is placed in the pan 17 and the drum 13 is revolved by means of the pulley 30 from any suitable source of power. As the cups 14 pass beneath the surface of the oil in the pan 17 they fill with oil which is carried upwardly on the rising side of the drum and deposited at the top into the trough 20.

The oil which adheres to the outer surface of the drum is prevented from dripping into the trough 20 by the bead 23 which deflects it back into the pan 17.

The oil which adheres to the inner surface of the drum is prevented from dripping into the trough 20 by the groove 22 which deflects it back into the pan 17.

The lifter bars 16 travel through the oil at an angle and act in the nature of propellers to constantly keep the oil in the pan 17 in circulation thereby keeping it in uniform consistency.

Should it be desired to decrease the amount of oil being delivered from the trough 20, the set screw 21 is loosened and the trough 20 pulled outward so as to receive the oil from a lesser number of the cups 14. Should it be desired to increase the amount of oil delivered, the trough 20 is forced inward to receive the oil from a greater number of cups. The range of adjustment of delivery is from one cup of oil per revolution, to the total number of cups of oil car-

ried by the machine, per revolution. Should it be desired to increase this range of adjustment in any way, this may be done by varying the speed at which the drum 13 is revolved. It will be noted, that the cups 14 are placed in staggered relation on the opposite sides of the drum 13, so that the amount of oil delivered may be increased or decreased, one cup at a time.

10 It is preferred to form the trough 20 in the shape shown in Fig. 5, that is with a dove tail shape in cross section, with flaring sides 24. The clamp 19 is shaped to grasp the dove tail bottom of the trough 20 by means of a movable block 25, which is pressed against the trough 20 by the set screw 21.

15 The drum 13 is preferably formed by rolling a triangular piece of sheet metal upon a circular drum 26, which is secured to the shaft 29, and clamping it thereon by means of a clamping ring 27 and a bolt 28.

20 While a specific form of the improvement has been described and illustrated herein, it is desired to be understood that the same may be varied, within the scope of the appended claims, without departing from the spirit of the invention.

Having thus described the invention, 30 what is claimed and desired to be secured by Letters Patent is:—

1. A liquid delivering mechanism comprising a series of liquid containers, arranged to rotate, the plane of said series being disposed at an angle to a perpendicular to the axis of said rotation; a pan from which said containers will carry said liquid and a trough into which said containers will pour said liquid, the extension of said trough 40 into said series being adjustable.

2. A liquid delivering mechanism comprising a shaft; a hollow cylinder concentrically mounted on one extremity of said shaft, the plane of the free edge of said cylinder being 45 at an angle to a plane perpendicular to the axis of said shaft; containers mounted along said free edge; a pan into which said cylinder depends; a trough extending within said

cylinder and means for varying the extension of said trough. 50

3. A liquid delivering mechanism comprising a liquid container; a hollow, horizontal, rotatably-mounted, cylinder extending within said container, one end of said cylinder being cut at an angle to a plane perpendicular to the axis thereof; cups secured along said angularly cut edge; an angularly disposed trough arranged to extend within said cylinder under the angularly cut edge thereof, the degree of extension of said trough within said cylinder being adjustable. 55

4. A liquid delivering mechanism comprising a liquid container; a hollow, horizontal, rotatably-mounted, cylinder extending within said container, one end of said cylinder being cut at an angle to a plane perpendicular to the axis thereof, said cylinder having angularly disposed bars on its interior to agitate said liquid; cups secured 60 along said angularly cut edge; an angularly disposed trough arranged to extend within said cylinder under the angularly cut edge thereof, the degree of extension of said trough within said cylinder being adjustable. 65

5. A liquid delivering mechanism comprising a liquid container; a hollow, horizontal, rotatably-mounted, cylinder extending within said container, one end of said cylinder being cut at an angle to a plane perpendicular to the axis thereof, said cylinder having angularly disposed bars on its interior to agitate said liquid; an obstruction encircling said cylinder adjacent its angularly cut edge to prevent said liquid from dripping from said edge; cups secured along said angularly cut edge; an angularly disposed trough arranged to extend within said cylinder under the angularly 80 cut edge thereof, the degree of extension of said trough within said cylinder being adjustable. 85

In testimony whereof, I affix my signature.

ARTHUR C. DAMAN.
